(57) **CLAIM**

The ornamental design for a flexible flying disc, as shown and described.

DESCRIPTION

FIG. 1 is a front view of a flexible flying disc;
FIG. 2 is a back view thereof;

FIG. 3 is a left side view thereof, the right side view being a mirror image thereof;

FIG. 4 is a top view thereof, the bottom view being a mirror image thereof; and,

FIG. 5 is a perspective view thereof.

The broken lines shown in FIG. 2 depict portions of the flying disc that form no part of the claimed design.

1 Claim, 5 Drawing Sheets
